UNITED STATES PATENT OFFICE

91,153

DESIGN FOR A SERVING WAGON

Clarine K. Grebenstein, Englewood, N. J.

Application June 26, 1933. Serial No. 48,539

Term of patent 3½ years

To all whom it may concern:

Be it known that I, CLARINE K. GREBENSTEIN, a citizen of the United States, residing at Englewood, in the county of Bergen and State of New Jersey, have invented a new, original, and ornamental Design for a Serving Wagon, of which the following is a specification, reference being had to the accompanying drawing forming a part thereof.

In the drawing:

The figure is a perspective view of the wagon.

The wagon is of the single wheel double handle type and of willow or rattan upon a wood frame, there being mounted upon intermediate portions of the handles a hamper-like enclosure within which miscellaneous goods may be carried.

I claim:

The ornamental design for a serving wagon substantially as shown and described.

In testimony whereof, I hereto affix my signature.

CLARINE K. GREBENSTEIN.
